[57] CLAIM

The ornamental design for a combined toothpaste tube
dispenser key and head with display space for advertising
or the like, as shown and described.

DESCRIPTION

FIG. 1 is a perspective view of a combined toothpaste tube
dispenser key and head with display space for advertising
or the like showing my new design;

FIG. 2 is a front elevational view thereof, the rear being
identical in appearance;

FIG. 3 is a side elevational view thereof, the opposite
side being identical in appearance;

FIG. 4 is a top plan view thereof; and

FIG. 5 is a bottom plan view thereof.

FIG.—1

FIG.—2

FIG.—3

FIG.—4
